UNITED STATES PATENT OFFICE.

HARRY A. HASELDEN, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

APPARATUS HAVING STOP-MOTIONS.

No. 867,181.

Specification of Letters Patent.

Patented Sept. 24, 1907.

Application filed June 23, 1906. Serial No. 323,010.

To all whom it may concern:

Be it known that I, HARRY A. HASELDEN, a citizen of the United States, residing at Whitinsville, in the county of Worcester and State of Massachusetts, have 5 invented certain new and useful Improvements in Apparatus Having Stop-Motions, of which the following, taken in conjunction with the accompanying drawings, is a full and true specification.

This invention relates to the stop motions of certain 10 combined apparatus, such as cotton combing apparatus, wherein one part, such as the draw-head thereof, delivers a continuous supply of sliver, and another part, such as the coiler, receives and operates upon said supply, and the invention consists in the provision of 15 means whereby the operator can temporarily render said stop motion inoperative on special occasions, as for example, when the sliver issuing from the draw-head has broken down and the sliver detector of the coiler apparatus has brought about a stoppage of the 20 machine, so that the operation of the machine may be continued while he repairs the sliver by splicing the broken ends, or otherwise restores the machine to its fully operative condition.

In the accompanying drawings, Figure 1 is an end 25 elevation of a part of a cotton combing machine showing the delivering rolls thereof in elevation and the coiler apparatus in vertical section, and also showing the stop motion apparatus and circuit partly in diagram; Fig. 2 is a top plan view of Fig. 1 with parts 30 shown in dotted lines and parts broken away; Fig. 3 is an enlarged side elevation of the circuit breaker with the insulation in section, and Fig. 4 is a top plan of Fig. 3.

In Figs. 1 and 2, A represents the end standard of a 35 cotton combing or other similar machine adapted to deliver its work, such as combed sliver in continuous form, and B represents the delivery rolls of the draw-head of said machine. The coiler apparatus is located adjacent the delivery rolls and is adapted to receive 40 the supply of sliver therefrom and coil it within the can C. The coiler apparatus is of usual construction and comprises an upright hollow frame-post D, at its upper end supporting the coiler head, which latter comprises a top plate D' within which the horizontal 45 coiler gear D² is mounted, said gear being provided with the usual inclined sliver conduit D³ and being peripherally supported upon an annular flange in the said plate wherein it is driven by a pinion E on the vertical coiler shaft E', which latter is driven by the 50 beveled pinions E² from the combing machine or other source of power. The coiler gear bonnet F carries the journals of the calender rolls G, which are located directly over the upper end of the sliver conduit D³ and geared together by the gears G' so as to be driven in 55 unison through the beveled pinions E³ by the afore-

mentioned shaft E' (see Fig. 2). The trumpet cover H surmounts the coiler gear bonnet and carries the trumpet H' above the calender rolls and also the pivoted sliver detector H². The cover H is pivoted to the casing or frame-post D at the point H⁴, and the bonnet F and attached parts are also removable from the head plate D'.

In the normal operation of the foregoing apparatus, the work or sliver, represented by the dotted line in Fig. 1, emerges from the rolls B and passes over the 60 sliver guide H⁵ and over the fork or spoon of the detector lever H², holding the same in the position indicated, and from thence the sliver passes through the trumpet and calender rolls into the sliver conduit D³ of the coiler gear by which means it is coiled in the 65 can.

The sliver detector has an arm within the cover H provided with a counter-balance which is so adjusted that in the normal working of the apparatus the weight or draft of the sliver on the spoon of the detector will 70 maintain the said arm elevated, but when said sliver breaks down or fails for any reason, the said arm falls to its operative position in which it brings about the actuation of the stop motion, causing an automatic 75 stoppage of the machine and thereby preventing waste 80 of material.

In the case under consideration, the stop motion comprises an electrical circuit and apparatus which, being of usual construction, is herein shown in diagram. Referring to Fig. 1, the stop motion comprises a source 85 of electric current K with one pole connected to the metallic frame of the machine and the other with one of the poles of a suitable electrical knock-off device L, which when energized shifts the driving belt of the machine or in some other way interrupts the supply and 90 motive power thereto; and the circuit continues from the other pole of the knock-off device by wire K', through a spring or gravity-returned circuit-breaker M, presently described, which is mounted within the hollow frame-post D, and from thence by wire K² to an insulated terminal spring O, which has separable contact with the hooked spring of the insulated detector contact P, the latter being carried by parts fixed to the removable bonnet F and directly beneath the weighted arm of lever H². In this position the said lever is 95 adapted to fall upon the end of the contact, and being itself in electrical contact with the metallic frame, thereby closes the circuit through the knock-off device and stops the machine, and as long as the said knock-off device remains energized the machine cannot be re- 100 started.

The circuit breaker M, above mentioned, comprises two spring leaves 1 and 2, respectively secured to opposite sides of a block of insulation 3 which is bolted to the side of the frame post D. The free ends of the two 110

springs are in mutual, spring-pressed contact and an aperture is provided in the lower leaf to receive the boss of a thimble 4 of insulating material which is inserted between the two springs. The upright rod 5, mounted 5 for reciprocation in the brackets 6 within the frame post, fits with its upper end in a socket in the said thimble and at its lower end is stepped upon the end of a pivoted foot treadle 7 or other part extending to the outside of the coiler post, whereby the operator can 10 move the rod a sufficient distance to spread apart the spring leaves and open the circuit. The elasticity of the upper spring leaf or the weight of the rod or connected parts, or both, tend to return the leaves to their normal closed position.

15 In order for the operator to piece broken ends or reinsert the sliver between the rolls G, when the machine has been automatically stopped by the action of the detector, he must first start the machine and keep it in motion until it has delivered a sufficient length of sliver 20 for this purpose. By operating the rod 5 he is enabled to open the circuit and hold the stop motion temporarily inoperative during this interval, so that after having started the machine by pulling the starting handle R, (Fig. 1) the machine will proceed to deliver 25 sliver notwithstanding the fact that the detector is momentarily in its circuit closing position.

By locating the circuit breaker at the upper end of its actuating rod and the treadle 7 near the base of the coiler, the operator may operate the circuit breaker 30 with his foot and enjoy the use of both hands in piecing, and upon the withdrawal of his foot, after the sliver has been restored, the circuit breaker returns to its normal condition by virtue of its spring or gravity, whereupon the stop motion is again fully operative for protecting 35 the machine.

The invention is not confined to the specific form of detector mechanism as herein illustrated nor to the special agency by which the stoppage of the apparatus is brought about. Other and additional detector apparatus 40 may also be employed if desired and other forms of circuit breakers will be equally as serviceable as that shown herein provided they are returned to normal position by spring or gravity.

In Fig. 1 the coiler gear bonnet is provided with an 45 additional contact terminal S connected with the contact terminal P by means of the wire S' and located

just above the rim of the coiler gear D². The stop motion circuit is closed at this point when the coiled sliver in the can C rises to such an extent that, crowding under the coiler gear, it raises it into contact with the end 50 of the terminal S thereby stopping the machine until the full can is removed and another inserted in its place; but if desired the full can may be removed without stopping the machine by holding the treadle down while the cotton is crowding under the coiler- 55 gear.

Having described my invention what I claim and desire to secure by United States Letters Patent is the following:

1. The combination of a machine adapted to deliver its 60 work in continuous form, an apparatus supplied by said machine having a detector adapted to cause the stoppage of said machine upon the failure of the supplied work, a device functioned to render said detector inoperative and adapted to be held and maintained in its effective position 65 for this purpose by the operator, and means tending to restore said device when released by the operator.

2. The combination of a sliver delivering machine, means for starting the machine, a stop motion circuit, an apparatus supplied by said machine having a sliver detector controlling said circuit, and an automatically-returned circuit-breaker for said circuit adapted to be held 70 by the operator in the position in which the said circuit permits the re-starting of the machine.

3. In apparatus of the kind described, a sliver-delivering 75 machine, and a coiler supplied thereby having an upright frame post, in combination with a stop motion apparatus adapted to cause the stoppage of the machine upon the failure of the sliver and means located near the base of the frame post for temporarily rendering said stop motion 80 apparatus inoperative.

4. In apparatus of the kind described, a coiler head, a supporting post therefor and a detector on said head, in combination with an upright movable rod supported by said post and means at the upper end of said rod, adapted 85 for actuation thereby, to render said detector inoperative.

5. In apparatus of the kind described, a coiler having a hollow frame post and a detector, in combination with a stop motion circuit controlled by said detector, a circuit breaker in said circuit mounted within said hollow frame 90 post, and means extending to the outside of the post whereby the operator may operate said circuit-breaker to render said circuit temporarily inoperative.

In testimony whereof, I have signed my name to the specification in the presence of two subscribing witnesses. 95

HARRY A. HASELDEN.
